UNITED STATES PATENT OFFICE.

FRED DE MIER, OF PICHER, OKLAHOMA, ASSIGNOR TO HIMSELF AND ARTHUR E. BENDELARI, OF PICHER, OKLAHOMA.

APPARATUS FOR CONCENTRATING ORES.

1,308,049.

Specification of Letters Patent.

Patented July 1, 1919.

Application filed April 26, 1918. Serial No. 230,874.

To all whom it may concern:

Be it known that I, FRED DE MIER, a citizen of the United States of America, and a resident of Picher, in the county of Ottawa, State of Oklahoma, have invented certain new and useful Improvements in Apparatus for Concentrating Ores, of which the following is a true and exact description, reference being had to the accompanying drawings, which form a part thereof.

My present invention comprises improvements in apparatus for concentrating ores by the so-called froth or flotation process, and the general object of my invention is to provide an efficient apparatus for the purpose specified, characterized by its simplicity of construction and ease and efficiency of operation, and particularly by the easy manner in which the rate of travel of the ore and its liquid vehicle through the apparatus may be regulated.

The various features of novelty which characterize my invention are pointed out with particularity in the claims annexed hereto and forming a part of this specification. For a better understanding of the invention, however, and the advantages possessed by it reference should be had to the accompanying drawings and descriptive matter in which I have illustrated and described a preferred embodiment of my invention.

Of the drawings:

Figure 1 is an elevation partly in section on the line 1—1 of Fig. 2.

Fig. 2 is a plan view of the apparatus with parts broken away and removed.

Fig. 3 is an end view of the apparatus, and

Fig. 4 is a partial section on the line 4—4 of Fig. 2.

The apparatus shown in the drawings comprises a row of vertical cells A' to A¹⁰, inclusive, the walls of which may advantageously be formed, as shown, by a suitably disposed wooden cribbing. At each side of this row of cells is located a spitzkasten or froth chamber B, each of which is divided up into a series of cells B', B², B³, B⁴, B⁵ and B⁶ by correspondingly located partition walls B¹⁰. As shown, there is one division wall B¹⁰ centrally disposed with respect to each of the cells A⁵, A⁶, A⁷, A⁸ and A⁹ in each spitzkasten B. The spitzkasten chambers B' communicate with the cells A⁴ and

A⁵ through bottom ports A⁴⁰ and A⁵⁰, respectively, and through upper ports A⁴¹ and A⁵¹, respectively. Similarly bottom ports A⁶⁰, A⁷⁰, A⁸⁰, A⁹⁰ and A¹⁰⁰, and upper ports A⁶¹, A⁷¹, A⁸¹, A⁹¹ and A¹⁰¹ connect the spitzkasten chambers B² to the cells A⁵ and A⁶; the spitzkasten chambers B³ to the cells A⁶ and A⁷; the spitzkasten chambers B⁴ to the cells A⁷ and A⁸; the spitzkasten chambers B⁵ to the cells A⁸ and A⁹, and the spitzkasten chambers B⁶ to the cells A⁹ and A¹⁰. As shown, each of the ports A⁴⁰, A⁵⁰, etc., A⁴¹, A⁵¹, etc., extends the full width of the cell into which it opens. F represents the ore or slime supply pipe discharging into the upper end of the chamber A', and G represents the gangue discharge pipes opening from the bottoms of the spitzkasten chambers B'. The rate of discharge through the outflow pipes G may be regulated by means of the simple plug cocks G' with which the outflow pipes G are provided.

Mounted in each of the vertical cells, except cells A' and A³, is a rotating agitator or beater C carried by a vertical spindle C', which is provided at its upper end with a pulley C². Each of the spindles C' is journaled at its upper end on an upper supporting beam C¹⁰, and also passes through a bearing block C⁴ which extends across the top of the corresponding vertical cell and supports a step bearing for the spindle. Each of these bearings comprises a collar C³ adjustably secured to the corresponding spindle C', as by a set screw C⁶, as indicated in Fig. 4, and a bearing plate C⁵ carried by the corresponding block C⁴ and against which the lower end of the corresponding spindle collar C³ bears. The vanes of each agitator C are slightly inclined and the agitator is rotated in such direction that it tends to create an upward flow through the vertical cell in which it is located. The agitating and froth producing effect of the agitators C may be individually adjusted by raising and lowering the collars C³. Bearings are provided at the outer edge of each froth chamber B for the usual rotatable froth transmitters E which sweep the froth with the metal held thereby into the froth collecting channels D at the sides of the chambers B.

The ore or slime entering cell A' passes out of the latter into the adjoining cell A² through a port located as indicated at A²⁰ 110

connecting the lower ends of these cells, and passes from the cell A² into the cell A³ through an upper port located at A²¹. From the cell A³ the slime passes into the lower end of the cell A⁴ through a port located at A³⁰. The oily agent for securing the desired froth effect is mixed with the slime either prior to the introduction of the latter into the chamber A', or in the latter chamber. The supply through the pipe F and the discharge through the cocks G' are so regulated that the liquid level, in the cells A⁴ to A¹⁰ and in the spitzkasten B, is kept below the froth collecting channels D at the sides of the chambers B.

In the preferred normal mode of use of my apparatus, the ore travels from the chamber A⁴ to the spitzkasten compartments B⁶ along a horizontal zigzag or serpentine path from the bottom of the cell A⁴ through the ports A⁴⁰ into the compartments B', from the latter into the cell A⁵ through the ports A⁵⁰, thence through the ports A⁵⁰ into the compartments B² and so on. The flow of the liquid along this horizontal serpentine path, supplemented by the agitating effect of the beaters C prevents the heavier particles of ore and gangue from collecting at and clogging the apparatus at any point. In each of the cells A⁴ to A¹⁰ the corresponding agitator beats more or less of the oily menstruum to a froth which as it rises to the top of the cell, carries with it more or less of the metal to be recovered. The froth passing into the upper portion of each spitzkasten compartment through the corresponding upper ports A⁴¹ to A¹⁰¹ is wholly or mainly removed therefrom in normal operation by the corresponding froth transfferer E since there is no appreciable tendency of the froth to pass from one spitzkasten compartment into another. The joint regulation of the rate of supply through the pipe F and the rate of withdrawal through the outlets G not only regulates the rate of liquid and ore flow through the apparatus, but also the liquid level therein and thereby contributes materially to the efficiency of operation under varying conditions.

While in accordance with the provisions of the statutes I have illustrated and described the best form of my invention now known to me, it will be apparent to those skilled in the art that changes may be made in the form of my invention without departing from its spirit, and that some features of my invention may sometimes be used to advantage without a corresponding use of other features of the invention.

Having now described my invention, what I claim as new and desire to secure by Letters Patent, is:

1. Flotation apparatus comprising in combination a series of spitzkasten compartments, a series of agitating cells having

lower ports connected with said compartments, all so arranged that each adjacent pair of said compartments are connected to one another through the lower end of a corresponding cell, and the lower ends of each adjacent pair of cells are connected to one another through a corresponding compartment, said cells also having upper froth outlets into said compartments, and means for agitating the contents of said cells.

2. Flotation apparatus comprising in combination a series of spitzkasten compartments, a series of agitating cells having lower ports connected with said compartments, all so arranged that each adjacent pair of said compartments are connected to one another through the lower end of a corresponding cell, and the lower ends of each adjacent pair of cells are connected to one another through a corresponding compartment, said cells also having upper froth outlets into said compartments, means for agitating the contents of said cells, and means for regulating the liquid supply to the initial cell of said series of cells and for regulating the liquid discharge from the final compartment of said series of compartments.

3. Flotation apparatus comprising in combination a series of spitzkasten compartments, a series of agitating cells having lower ports connected with said compartments, all so arranged that each adjacent pair of said compartments are connected to one another through the lower end of a corresponding cell, and the lower ends of each adjacent pair of cells are connected to one another through a corresponding compartment, said cells also having upper froth outlets into said compartments, and upwardly acting rotary impeller agitators mounted in said cells.

4. Flotation apparatus comprising in combination a series of spitzkasten compartments, a series of agitating cells having lower ports connected with said compartments, all so arranged that each adjacent pair of said compartments are connected to one another through the lower end of a corresponding cell, and the lower ends of each adjacent pair of cells are connected to one another through a corresponding compartment, said cells also having upper froth outlets into said compartments, and vertically adjustable upwardly acting rotary impeller agitators mounted in said cells.

5. Flotation apparatus comprising in combination a row of vertical agitating cells, a row of spitzkasten compartments at each side of said row of cells, said cells having lower ports communicating with said compartments and upper froth outlets into said compartments, said cells, compartments and lower ports being so relatively arranged that each adjacent pair of compartments in each row are connected to one another through

the lower end of a corresponding cell, and the lower ends of each adjacent pair of cells are connected to one another through a corresponding compartment in each row of 5 compartments, and means for agitating the contents of said cells.

6. Flotation apparatus comprising in combination a row of vertical agitating cells; a row of spitzkasten compartments, at each 10 side of said row of cells, said cells having lower ports communicating with said compartments and upper froth outlets into said compartments, said cells, compartments and lower ports being so relatively arranged that 15 each adjacent pair of compartments in each row are connected to one another through the lower end of a corresponding cell, and the lower ends of each adjacent pair of cells are connected to one another through a corresponding compartment in each row of 20 compartments, and means for agitating the contents of said cells comprising an up-

wardly acting vertically adjustable rotary impeller in each cell.

7. Flotation apparatus comprising in combination a row of vertical agitating cells, a row of spitzkasten compartments, at each side of said row of cells, said cells having lower ports communicating with said compartments and upper froth outlets into said compartments, said cells, compartments and lower ports being so relatively arranged that each adjacent pair of compartments in each row are connected to one another through the lower end of a corresponding cell, and 30 the lower ends of each adjacent pair of cells are connected to one another through a corresponding compartment in each row of compartments, means for agitating the contents of said cells, and means adjacent the 35 upper outer edges of said compartments for removing froth therefrom.

FRED DE MIER.
